Attorney

UNITED STATES PATENT OFFICE.

ISIAH CONRAD, OF COLUMBUS, OHIO, ASSIGNOR TO F. O. SCHOEDINGER, OF COLUMBUS,
OHIO.

PORTABLE AND COLLAPSIBLE TABLE OR TRAY.

Application filed August 8, 1925. Serial No. 49,097.

This invention relates to an improved portable and collapsible table or tray, and is particularly directed to an improved form of sheet metal tray capable of being used in hospitals or sick rooms for the purpose of supporting and receiving food dishes and the like upon the bed so that a patient may occupy a comfortable, semi-reclining position while using the table.

10 In accordance with the invention there is provided a table for the purpose specified which consists of a tray or supporting plate to the ends of which are pivotally connected a pair of supporting frames, so arranged that when the table is in use the frames will occupy a vertical position permitting of the support of the tray or plate in a horizontal plane above the limbs or body of the user when the table is positioned upon the bed 20 of the patient, there being associated with the end frames a novel form of locking means for retaining the frames in their vertical extended positions, the said frames being extended above the plane of the plate so as to provide manipulating portions permitting of the grasping of the table and the convenient handling and lifting of the same. The said frame members being pivoted so that when the table is not in use, the frames 30 may be collapsed to lie substantially in the plane of the tray and to enable the table proper to utilize but a minimum of storage space.

With these and other objects in view, as 35 will appear as the description proceeds, the invention consists in the novel features of construction, combinations of elements and arrangements of parts hereinafter to be fully described and pointed out in the appended 40 claim.

In the accompanying drawing:

Figure 1 is a side elevation of a tray or table constructed in accordance with the present invention,

45 Figure 2 is a partial top plan view thereof, Figure 3 is an end elevation,

Figure 4 is a detail vertical sectional view disclosing the manner of pivoting the end frames to the tray, and

50 Figure 5 is a horizontal sectional view on the line 5—5 of Figure 4.

Referring more particularly to the drawings my improved hospital table or tray con-

sists of a horizontally disposed preferably sheet metal plate 1, provided with down-turned marginal flanges 2 around the edges thereof. Secured to the inner surfaces of the flanges 2 at the ends of the plate 1 is a pair of reinforcing bars 3 which are provided with vertically disposed lugs or bearings 4. The lower ends of these lugs are bent outwardly so as to extend beyond the edges of the plate 1 as indicated in Figures 4 and 5.

Pivoted as at 5 to the out-turned ends of the lugs 4 are pivotally movable leg or frame members 6. In this instance the leg or frame members are formed from bent tubing and the contour thereof is best disclosed by reference to Figure 3. In this figure it will be observed that each leg or frame member includes a pair of vertically disposed legs 7 which terminate at their lower ends in curved portions 8, are then bent upwardly to provide converging legs 9 which terminate at their upper ends in arcuate connecting portions 10, the upper ends of the legs 7 being extended above the plane of the plate 1 and are connected by horizontally disposed cross portions 11. The portions 11 by being located above the plate 1 permit the frames to be conveniently grasped so that the tray may be carried from place to place. Also, the shape of the portions 7, 8 and 9 of the frame member 6 is such as to permit the tray to assume quite a stable condition when the tray or table is placed upon a soft mattress or bedding.

When not in use the frame members are swung about the pivots 5 so instead of extending perpendicularly to the plate 1, the said leg members will lie substantially in the plane of the plate 1. By thus collapsing the table convenience is to be had in storing the same compactly. Since the cross portion 95 11 of the frame members will extend above the end of the plate 1, it will be used as a hook for permitting of the expansion or support of the table from an adjacent wall or the like. To maintain the frame members in their vertical positions at right angles to the plate 1, the said frame members in this instance are provided with integral laterally projecting hooks 12. These hooks are arranged to engage with spring tongues 13, 100 carried in connection with the vertically ar-

ranged back wall or ledge 14 of the plate. It will be manifest that as the frame members are moved about their pivots in a direction causing the leg members to assume their up-right positions, the hooks 12 thereof will be forced into engagement with the spring tongues 13, so that the latter may respond in frictionally holding the frames against undue movement.

10 In view of the foregoing description, taken in connection with the accompanying drawing, it will be seen that there is provided a simple and useful form of hospital tray which will provide convenience in many respects in supporting articles for patients assuming a reclining or semi-reclining position in a bed. The table is of such construction that when set up for use the same is particularly rigid and stable, not apt to 15 tilt and may be placed so that the articles deposited thereon may be conveniently reached by the patient without causing the latter to twist or assume a cramped, unnatural position. The device is of very simple

construction and can be operated with utmost convenience.

25 What is claimed is:

In a folding table of the character set forth, a supporting plate including down-turned marginal flanges, lugs formed with the end flanges of said plate, foldable end frames for said plate pivoted to said lugs whereby said frames are capable of being moved from inactive positions lying substantially in the plane of said plate to active positions occupying planes substantially at right angles to that of said plate, each of said frames being formed to include transversely spaced longitudinally extending side bars, a connecting upper bar and a loop shaped leg connection between the lower ends of the side bars, an offset arm provided upon one of said side bars, a spring means engaging with the arm of each of said frames for retaining the latter locked in 30 their active vertical positions.

35 In testimony whereof I affix my signature.

40 ISIAH CONRAD.
